Primary Examiner—Nelson C. Holtje
Attorney, Agent, or Firm—Brinks Hofer Gilson & Lione[57] **CLAIM**

The ornamental design for a clock face, as shown and described.

DESCRIPTION

FIG. 1 is a front elevational view of a clock face showing my new design;

FIG. 2 is a front elevational view showing a modified form of my new design;

FIG. 3 is a front elevational view showing an even further modified form of my design; and,

FIG. 4 is a front elevational view showing yet an even further modified form of my new design.

The clock face is conventionally of no appreciable thickness and the rear is flat and unornamented.
